UNITED STATES PATENT OFFICE.

ALEX J. BURG, OF ST. PAUL, MINNESOTA.

COUNTER BIN.

Application filed April 30, 1927. Serial No. 187,803.

The present invention relates to an adjustable bin structure.

In department and similar stores it is desirable to display large numbers of different classes of small items upon a counter and in order to attractively display these items, without permitting the different classes thereof to become confused with each other, it is customary to provide enclosures of plate glass 16 in the form of small bins. The pieces of plate glass forming the sides of the bins are customarily supported between blocks of wood which are cut to the size of the required bins and hold the strips of plate glass in position by the weight of the wooden blocks resting 21 upon the counter or table top. In handling the merchandise displayed in bins of this character the wooden blocks forming the supports for the plate glass strips are frequently 26 displaced, causing the glass sides to fall or lean to one side and permitting the merchandise from one of the bins to escape into adjacent bins. This results in an untidy appearance of the display, and confusion of the 31 merchandise.

The present invention has for its object the making of an adjustable bin support which is adapted to the construction of bins of different sizes by employing base units constructed 36 to supportingly engage glass partition members to firmly hold them in position.

In order to attain this object, there is provided, in accordance with one feature of the invention, a plurality of blocks slidably mounted upon support members and having 41 means for resiliently drawing the blocks together, to support the bin partition members therebetween.

These and other features of the invention will be more fully brought out in the following description and accompanying drawings, 46 wherein:

Figure 1, is a view in perspective of a device made in accordance with the present invention.

Figure 2, is a view in transverse section on the line 2—2 of Figure 1.

Figure 3, is an enlarged fragmentary sectional view in perspective of a plurality of bins constructed in accordance with the present invention; and

Figure 4 is a partial perspective of the device assembled.

Referring to the drawings in detail a plurality of base blocks 1 are provided with 51 openings 2 and 3 therethrough through which

are inserted support members 4 which in the present instance are of wooden doweling. The base blocks are mounted upon the dowels to have a sliding fit thereon so as to be freely 60 adjustable longitudinally of said dowels. A central hole 5 is drilled through each of the blocks parallel to the dowels, in which hole is mounted a coil spring 6 affixed to the block on each end of the assembly by means of a brad 65 7 which enters a loop 8 in each end of the spring to firmly hold it in position within said block. An angular retaining plate 9 is affixed to the outside edges of the end blocks of each assembly, the vertical portion of said 70 plate being spaced outwardly from the edge of the block 1 by means of a wooden spacing strip 10. These angular plates may be screwed to the blocks by means of wood screws, not shown. A plurality of filler strips 11, which 75 may be of wood, and of the same thickness as the glass of which the partitions are formed, are provided, to replace a glass strip where a bin larger than the base block 1 is 80 required. These strips are of a width which 85 will bring the top edge of said strips flush with the top of the blocks between which they are positioned when said strips are resting upon the dowels 4 upon which the blocks are mounted. Each assembled unit of blocks is 90 of a length equal to the width of the counter upon which it is to be used. By placing a plurality of the assemblies side by side, as shown in Figure 4, any required amount of bin space may readily be provided. The assemblies on either end of the counter are 95 constructed with an angle plate 9 on one end of each block to receive a glass end strip 12, while the interior assemblies are constructed with the angle plates on the outer sides of the front and rear blocks only to receive the front 100 and rear glass strips 13 and 14.

To construct bins upon a counter with the present apparatus it is first determined approximately the number and size of bins required. A number of assembly units are then placed upon the counter to lie transversely thereof and glass partition members 15 or filler strips 11 are inserted between the blocks thereof to form bins of the size required. A glass end strip 12 is then inserted 105 in the angle plates 10 on the outer sides of the end assembly units, and a second glass strip 16 is placed against the inner face of this assembly unit. A second assembly unit is then 110 placed closely against the glass strip 16 to support it. This process is repeated until

- the required number of bins are formed, when another end assembly unit is employed having angle plates 10 on the outer side thereof and a second glass end strip similar to the end strip 12 is inserted in the angle plates 10. Front and rear glass strips 13 and 14 are then inserted in the angle plates 10 on the outer ends of the assembly units and the structure is completed.
- 10 To change the size of any of the bins it is simply necessary to lift out any of the partitions 15 or filler strips 11 and replace them with filler strips or partitions, as required. By providing assembly units of different widths any size of bin may be readily provided.
- I claim:
1. A counter bin structure, comprising longitudinal support members, a plurality of base blocks slidably mounted thereon, means interconnecting said base blocks to resiliently draw them together, and division wall plates removably inserted between the blocks to divide the structure into bins.
  2. A counter bin structure, comprising a plurality of base blocks mounted in groups, means interconnecting adjacent base blocks of each group to resiliently draw them together, and division wall plates removably inserted between the blocks to divide the structure into bins.
5. A counter bin structure, having a plurality of blocks resiliently interconnected to be drawn together and separable a sufficient distance to receive a division wall plate between adjacent blocks, the resilient action drawing the blocks together to hold the division wall plates in position.
6. A counter bin structure, comprising a plurality of base block units interconnected by means resiliently holding the blocks together, strip means along the outer edges of said units to form wall supporting channels, and wall plates insertable between the units and in the channels to form bins.
7. A counter bin structure, comprising built-up base units having each a plurality of blocks slidably mounted on a longitudinal support member, means interconnecting said blocks to resiliently draw them together, and division wall plates removably inserted between the blocks and between adjacent base units to form a counter bin structure.
8. A counter bin structure, having a plurality of blocks resiliently interconnected to be drawn together and separable a sufficient distance to receive a division wall plate between adjacent blocks, the resilient action drawing the blocks together to hold the division wall plates in position.

In testimony whereof I affix my signature.

ALEX J. BURG.
